(57) CLAIM

The ornamental design for a kitchen carpet runner, as shown and described.

DESCRIPTION

FIG. 1 is a front perspective view of a kitchen carpet runner showing my new design;

FIG. 2 is a rear perspective view thereof;

FIG. 3 is a top plan view thereof;

FIG. 4 is a bottom plan view thereof;

FIG. 5 is a left size elevational view thereof;

FIG. 6 is a right side elevational view thereof;

FIG. 7 is a front elevational view thereof;

FIG. 8 is a rear elevational view thereof; and,

FIG. 9 is a rear exploded perspective view thereof.

The dashed lines on the rear surfaces depict tape portions positioned about the connection edges of the various carpet segments that form no part of the claimed design. The long-dashed broken lines showing a carpet section, text, and tape depict portions of the kitchen carpet runner that form no part of the claimed design. The remaining fine broken lines represent stitching, and are part of the claimed design. The stippling represent a contrast in appearance.
